UNITED STATES PATENT OFFICE.

JOSEPH WALTER DRUMMOND, OF CHILLICOTHE, OHIO.

SPARK-PLUG.

1,307,088.

Specification of Letters Patent. Patented June 17, 1919.

Application filed September 21, 1918. Serial No. 255,120.

To all whom it may concern:

Be it known that I, JOSEPH W. DRUMMOND, a citizen of the United States, and a resident of Chillicothe, in the county of Ross and State of Ohio, have invented certain new and useful Improvements in Spark-Plugs, of which the following is a specification.

My present invention relates generally to spark plugs, and more particularly to an anti-fouling plug the structure of which is simple, durable, and efficient, my object being the provision of a plug which will develop an extremely hot burning spark and will throw off grease and other carbon producing matter in action.

In the accompanying drawing which illustrates my present invention,

Figure 1 is a side view partly in elevation and partly in section showing a spark plug embodying my invention,

Fig. 2 is an end view thereof, and

Fig. 3 is an end view illustrating a slightly modified form.

Referring now to these figures, my improved spark plug, as to the general construction of its body, may be of various forms. In the present instance, I have shown a spark plug consisting of a shell 10, the inner end of which is externally threaded at 11, and the outer end of which has an external polygonal surface 12 and internal threads 13. This shell has a chamber 14 within its inner end into which the inner end 15 of the insulator 16 projects, and the shell has an intermediate counter-bore 17 in which the annular enlarged intermediate portion 18 of the insulator is seated. The insulator is held by a gasket nut 19 which screws within the outer internal threaded end 13 of the shell 10.

A central electrode 20 extends axially through the insulator 16 as is usual, its inner end projecting axially through the chamber 14 of the shell 10 to a point contiguous to the inner end of the said shell, the outer end of the electrode projecting beyond the outer end of the insulator 16 being as usual provided with the lead clamping nut 21.

My present invention is applied to the inner end of the shell 10 and consists of a conical or a frusto-conical electrode 22 which tapers inwardly within the chamber 14 and which has an opening 23 through which the effective end of the central electrode projects, the opposite or larger end of the said

electrode 22 having a flange 24 within the inner end of the shell 10, whose outer surface is preferably flush with the said inner end of the shell.

As seen in Fig. 2, flange 24 is preferably provided with a series of openings 25, said series extending entirely around the electrode 22 in order to permit of the discharge of the burned and powdered carbon from the chamber 14, the tapering outer surface of the cone shaped electrode 22 acting as a guide to direct the powdered carbon toward the openings 25 as it falls.

The opening 23 at the smaller end of the cone-shaped electrode 22 is sufficiently great in diameter as compared to the diameter of the central electrode 20 to bring about approximately the correct spacing between the electrodes, and extending as it does entirely around the central electrode, the electrode 22 of the shape described will bring about a heavy hot spark which will play entirely around the central electrode and will obviously burn the carbon as fast as it collects. The carbon being burned as it collects upon the electrode 22, the tapering surfaces of the latter assist in freeing the powder and thus obviating fouling of the plug either by means of collecting dry carbon of the accumulation of oil which in the ordinary type of plug embodying spaced spark points only, quickly forms an insulation and causes the plug to go dead.

I have found that the spark plug as proposed by my invention is particularly effective for the above purposes, and while it is not essential that the flange 24 of the electrode 22 within the inner end of the shell 10 be provided with openings 25, as will be seen by reference to Fig. 3 wherein the flange 24 is shown without openings, these openings materially increase the capacity of the plug to throw off the burned and powdered carbon as previously described.

The electrode 22 of the shape and structure described might be formed integral with the inner end of the shell 10 but may without complicating the manufacture of the said shell, be formed separate therefrom and either forced or shrunk therein to the position shown and described.

I claim:

1. A spark plug having a cylindrical shell, a main axial electrode insulated from the shell, and a frusto-conical electrode tapering inwardly from the inner end of the shell

and having an opening at its smaller inner end through which the axial electrode passes, the larger end of the said frusto-conical electrode having a flange joining the same to the inner end of the shell and provided with openings therethrough for the purpose described.

2. A spark plug including an axial electrode, a cylindrical shell having at its inner

end an inwardly tapering conical member 10 forming a second electrode, and provided with a series of openings in its said end around the larger end of the conical electrode, said conical electrode having an opening at its smaller inner end to receive the 15 axial electrode, as described.

JOSEPH WALTER DRUMMOND.
